UNITED STATES PATENT OFFICE.

JOSEPH W. FERGUSON, OF ROCKWOOD, TENNESSEE, ASSIGNOR OF ONE-HALF TO W. J. STEERE AND ONE-HALF TO JAMES A. HUFF, BOTH OF ROCKWOOD, TENNESSEE.

TRIMMING AND CLEANING ATTACHMENT.

1,259,382.

Specification of Letters Patent. Patented Mar. 12, 1918.

Application filed April 18, 1917. Serial No. 163,082.

To all whom it may concern:

Be it known that I, JOSEPH W. FERGUSON, a citizen of the United States of America, residing at Rockwood, in the county of Roane and State of Tennessee, have invented 5 certain new and useful Improvements in Trimming and Cleaning Attachments, of which the following is a specification, reference being had therein to the accompanying drawing.

This invention relates to trimming machines used in making seamless stockings and the like, and has for its object the production of a simple and efficient brush attachment for loosening and brushing off all 15 lint or other extraneous matter from the seam of the knit fabric.

Another object of this invention is the production of an efficient trimmer whereby 20 the cutting edges of the trimming knives will have a natural clearance while being operated.

With these and other objects in view, this invention consists in general of certain novel 25 combinations, constructions and arrangements of parts as will be hereinafter fully described and claimed.

In the drawings:—

Figure 1 is a top plan view of the improvement applied to a looper.

Fig. 2 is a front elevation of the structure shown in Fig. 1.

Fig. 3 is a section taken on line 3—3, Fig. 1.

Fig. 4 is a section taken on line 4—4, Fig. 1.

Fig. 5 is an enlarged top plan view of the means for supporting the brush and brush-operating means.

Fig. 6 is a top plan view of the brush-operating means in a partly swung position.

Fig. 7 is a section taken on line 7—7, Fig. 1.

Fig. 8 is a section taken on line 8—8, Fig. 3.

Fig. 9 is a section taken on line 9—9, Fig. 5.

Fig. 10 is a section taken on line 10—10, Fig. 5.

Fig. 11 is a section taken on line 11—11, Fig. 5.

By referring to the drawings it will be seen that 1 designates the bed-plate upon which is mounted the usual point ring 2.

55 An eccentric driving wheel 3 is supported

adjacent the bed-plate 1 and carries an eccentric pin 4, which pin 4 engages a pitman rod 5, as clearly shown in Fig. 1. This pitman rod 5 carries a socket plate 6 at the outer end thereof, as shown clearly in detail in Fig. 10, and this socket plate 6 is provided with a ball-receiving socket 7 into which ball-receiving socket 7 fits the ball joint 8 of the journal pin 9 carried by the rock arm 10. This ball joint 8 is held 65 against removal from the socket 7 by means of a gripping screw 11 extending through the outer end of the socket plate 6.

A standard 12 is supported upon a bracket 13 carried by the bed-plate 1 and this standard 12 carries a brush-supporting arm 14, which brush-supporting arm 14 is provided with an integral depending sleeve 15 through which the brush-carrying shaft 16 extends. This brush-carrying shaft 16 75 carries a brush head 17 at the lower end thereof, which brush head is provided with a pair of segmental brush fingers 18 arranged diametrically with respect to each other. Suitable bristles 19 are carried by 80 the brush fingers 18, as shown clearly in Fig. 11 of the drawings. A crank arm 20 is connected to the upper end of the brush-supporting shaft 16 and this crank arm 20 is held in engagement with the shaft 16 by 85 means of a set screw 21. An operating link 22 is held in engagement with the crank arm 20 by means of a set screw 23 and this link 22, as shown clearly in Figs. 1 and 6, is connected at its outer end to the connecting 90 screw 24 carried by the rock arm 10. This rock arm 10 is provided with a stub finger 25 extending substantially at right angles to the main arm of the rock arm 10, and this stub finger 25 carries a clamp 26, which clamp 26 95 engages a knife-operating link 27. The outer end of this link 27 is pivotally connected to a knife-operating arm 28, and this knife-operating arm 28 is carried by a rock shaft 29, as shown clearly in Fig. 4 of the drawings. 100

A stationary knife support 30 is connected to the standard 12 and this stationary knife support 30 comprises a substantially arc-shaped knife holder within which is mounted 105 a stationary knife blade 31, shown clearly in Fig. 4 of the drawings. This knife blade 31 is firmly clamped within a clamping socket 32 by means of a clamping screw 33. A suitable handle 34 is carried by the blade 110

- 31 for the purpose of permitting the same to be adjusted in the proper position within the knife holder 30. This stationary knife support 30 is provided with an overhanging 5 arc-shaped arm 35 which arm carries a journal 36 at the outer end thereof for supporting the rock shaft 29. A swinging knife support 37 is supported upon the rock shaft 29 and a knife-engaging hanger 38 is 10 adjustably mounted upon the support 37 and is provided with a longitudinally-extending slot 39 through which a binding screw 40 passes for holding the adjustable hanger 38 in an adjusted position upon the support 37. 15 A blade-gripping shoe 41 is carried by the adjustable hanger 38 and this shoe 41 is provided with a spring jaw 42 which is adapted to firmly clamp the swinging knife blade 43 in a set position upon the shoe 41. The 20 knife blade 43 is preferably dove-tail in cross-section for fitting in the knife-blade receiving socket 44. A suitable clamping screw 45 is employed for locking the spring jaw firmly around the knife blade 43. A 25 suitable adjusting screw 46 is carried by the upper ends of the support 37 and fits within a suitable receiving notch 47 formed in the hanger 37. This adjusting screw 46 engages the upper end of the hanger 38 for the purpose of permitting the same to be adjusted to a fine degree of accuracy. A binding screw 48 is carried by the adjustable hanger 38 and engages one end of the rock shaft as 30 shown in Fig. 8 of the drawings. 35 A guard plate 49 is carried by an arm 50 which is supported upon a clamp 51 carried by the standard 12 and this clamp 51 fits directly below the clamp 52 of the stationary knife-blade support 30. This clamp 40 51 and the clamp 52 are anchored together against independent rotation by means of a locking screw 53 and this locking screw 53 passes through a plate 54 anchored upon the clamp 52 by means of the screw 55. 45 A suitable push-back plate 56 is suspended below the blades of the cutting knife, as shown in Fig. 3, upon a depending pin 57, and this plate 56 is engaged by means of a coil spring 58 similar to the structure shown 50 in the patent to W. J. Steere, No. 916,799, issued on March 30, 1909.
- The operation of the device is as follows: The arm 28 is oscillated from side to side, thereby rocking the rock shaft 29 and swinging the swinging cutting blade 43 over the cutting edge 43' of the stationary cutting blade 31 and severing the fabric at a proper or desired point.
- Simultaneously with the operation of the 60 rock shaft 29 it will be seen that the link 22 will also be operated for rotating the brush-supporting shaft 16, thereby bringing the bristles 19 of the brush head 17 over the edges of the fabric which has been cut for the purpose of loosening and brushing off all

lint or other extraneous matter upon the seam of the knit fabric, such for instance as upon the seam which has been made at the toe of a seamless stocking and the like.

From the foregoing description it will 70 be seen that a very simple and efficient means has been produced for effectively operating the brush and causing the same at all times to efficiently brush the lint or other extraneous matter from the seam of 75 the fabric.

Attention is especially invited to Fig. 4 of the drawings for it will be seen that the rock shaft 29 is positioned at a point to the left of the cutting edge of the stationary 80 cutting blade 31, thereby causing the cutting edge of the swinging blade 43 to be naturally lifted out of engagement with the stationary blade for passing the cutting edge of the stationary blade 31, thereby preventing the cutting edge of the stationary blade from wearing or rubbing upon the body of the stationary blade 31. This arrangement will add considerable to the life 85 of both the swinging blade 43 and also the 90 stationary blade 31.

What is claimed is:—

1. In a trimming and cleaning attachment, a trimming means, of a brush support, a brush-carrying shaft extending vertically 95 through said brush support, a brush head carried by the lower end of said brush-supporting shaft, said brush head provided with a plurality of radiating bristle-supporting clamps, bristles extending downwardly from 100 said clamps, a crank arm connected to the upper end of said brush-supporting shaft, an operating link connected to said crank arm, a rock arm carried by said support and engaging said link for operating said link 105 and rotating said brush, a pitman rod connected to the outer end of said rock arm, and means for actuating said pitman rod.

2. In a trimming and cleaning attachment, a trimming means, a brush support, a brush-carrying shaft extending vertically through said brush support, a brush head carried by the lower end of said brush-supporting shaft, said brush head provided with a plurality of radiating bristle-supporting 110 clamps, bristles extending downwardly from said clamps, a crank arm connected to the upper end of said brush-supporting shaft, an operating link connected to said crank arm, a rock arm carried by said support and engaging said link for operating said link 115 and rotating said brush, a pitman rod connected to the outer end of said rock arm, said rock arm provided with a stub finger connected thereto, a rock shaft, trimming means 120 connected to said rock shaft and a link connecting said stub finger and rock shaft for rotating said rock shaft as said rock arm is operated.

3. In a trimming and cleaning attach- 130

ment, a support, a trimming device carried thereby, a brush-supporting arm carried by said support, a rock arm carried by said support, means connecting said rock arm to said trimming device and brush-supporting arm, a brush carried by said brush-supporting arm and adapted to be actuated thereby, a pitman rod for actuating said rock arm, said pitman rod provided with a socket plate at 10 the outer end thereof, a locking screw car-

ried by said socket plate, a ball joint depending from said rock arm and fitting in said socket plate, said screw engaging said ball for preventing the disengagement of said rock arm with said socket plate, and means 15 for actuating said pitman rod.

In testimony whereof I hereunto affix my signature.

JOSEPH W. FERGUSON.
